UNITED STATES PATENT OFFICE.

BENJAMIN P. MCKINLEY, OF FOREST HILLS, NEW YORK, ASSIGNOR TO HEMCO ELECTRIC MANUFACTURING COMPANY, INC., OF LONG ISLAND CITY, NEW YORK, A CORPORATION OF NEW YORK.

DESIGN FOR AN ATTACHMENT-PLUG CAP.

Application filed October 8, 1925. Serial No. 15,063. Term of patent 14 years.

To all whom it may concern:

Be it known that I, BENJAMIN P. MCKINLEY, a citizen of the United States, residing at Forest Hills, in the borough and county of Queens, city and State of New York, have invented a new, original, and ornamental Design for an Attachment-Plug Cap, of which the following is a specification, reference being had to the accompanying drawing, forming a part thereof, in which—

I claim:

The ornamental design for the attachment plug cap, as shown.

BENJAMIN P. MCKINLEY.
